UNITED STATES PATENT OFFICE.

WALTER F. KEENAN, JR., OF NEW YORK, N. Y., AND DAVID D. THOMAS, OF BALTIMORE, MARYLAND, ASSIGNORS TO POWER SPECIALTY COMPANY, OF NEW YORK, N. Y., A CORPORATION OF NEW YORK.

SUPERHEATER FOR MARINE BOILERS.

1,282,851.

Specification of Letters Patent. Patented Oct. 29, 1918.

Application filed April 24, 1917. Serial No. 164,116.

To all whom it may concern:

Be it known that we, WALTER F. KEENAN, Jr., and DAVID D. THOMAS, both citizens of the United States, residing, respectively, at 5 New York, in the county and State of New York, and at Baltimore, and State of Maryland, have invented certain new and useful Improvements in Superheaters for Marine Boilers, of which the following is a full, 10 clear, and exact description.

Certain forms of marine boilers are provided with air heater tubes, which generally described, are tubes in the flue or stack through which pass the heated products of 15 combustion and which are utilized to impart heat to the air for combustion forced around them and carried by means of ducts to the furnace. Boilers equipped with this device have certain peculiarities of construction 20 which have to be taken into consideration in case it be desired to add to them a steam superheater.

This problem we have solved by the construction and arrangement of a superheater 25 upon which is based our present application and which, in general terms, may be described as a superheater extending entirely across the uptake between the boiler and the air heater tubes, and supported from a 30 vertical partition wall in the rear part of the uptake at such a distance from the boiler tube sheet as to form a passage from the air heater tube chamber to the fire box. The front of the superheater is secured to the 35 front wall of the uptake or to a plate secured over an opening therein.

This general plan of construction and the details of construction necessary for carrying 40 it into effect are shown in the accompanying drawings in which—

Figure 1 is a vertical longitudinal sectional view of a boiler equipped with our improvement.

Fig. 2 is a part elevation and part cross- 45 sectional view of the same.

Fig. 3 is an enlarged detail view of the means of supporting the superheater elements from the aforesaid partition.

Fig. 4 is an enlarged detail of a part of 50 a supporting plate secured to said partition.

The boiler represented is one adapted to burn an oil fuel and comprises a set of boiler tubes A, a furnace B, and a chamber C for

the products of combustion from which they pass through the tubes A to the uptake D. 55

Between the latter and the stack are a series of air heater tubes E through which the waste products of combustion pass, and these are arranged in a compartment or passage F through which air is drawn or forced over or around the hot tubes and directed through the passage G into the inclosed space H, from which it is forced through adjustable doors or dampers K into the furnace. This is a well known type of 60 boiler and is modified to meet the requirements of the present invention only in the provision of the supporting diaphragm or plate L for the rear ends of the superheater.

The superheater, preferably of the now 65 well known Foster type, is located in the uptake above the boiler tubes and beneath the air heater tubes, and extends across substantially the whole of this space, so as to receive the maximum absorption of heat 70 without sensibly interfering with the draft. The rear bends W of the superheater elements pass through inclined slots M in a plate N which is removably secured to brackets O on the diaphragm plate L by bolts P passing through the brackets and angle plates R on the said plate N. This supports the rear end of the superheater and protects the bends from the direct action 75 of the hot gases.

The ends of the superheater tubes at the front pass through the wall of the uptake into a compartment S where they are connected with the headers T or cross connections V.

The details of the structure as a whole are not shown further than is necessary to illustrate the general plan of construction and operation of the same, and the part played by the superheater.

The special means for securing the latter in position by the slotted plate at one end and the wall of the uptake at the other so that the ends of any element may be disconnected from the wall and the plate removed to release the bends, is not claimed in this application as a part of our invention.

What we claim is:—

1. In a steam boiler equipped with air 105 heater tubes in its flue, the combination

- with the said tubes of a partition or dia-
phragm secured in the flue at such distance
from the rear wall as to form a passage-
way for the heated air to pass on its way
5 to the fire box, a plate removably secured
to brackets and in proximity to such par-
tition, and a superheater, the bends of the
straight tubes of which are supported in
slots in the said plate and the front ends of
10 which pass through the flue wall, the said
tubes extending entirely across the flue
under the air heater tubes and in line with
the greater dimension of the space therefor,
as set forth.
- 15 2. In a steam boiler equipped with air
heater tubes in its flue, the combination with
the said tubes of a partition or diaphragm

secured in the flue at such a distance from
the rear wall as to form a passage-way for
the heated air to pass on its way to the fire 20
box, brackets secured to said partition, a
plate removably secured to said brackets,
and a superheater the tubes of which ex-
tend across the flue, having its bends at the
rear supported in slots in said plate and its 25
rear ends secured in the flue wall and pro-
jecting through the same for connection
with headers and connections in a compart-
ment outside the same.

In testimony whereof we hereunto affix
signatures.

WALTER F. KEENAN, Jr.
DAVID D. THOMAS.
